GAS HEATER

Original Filed Nov. 14, 1925 2 Sheets-Sheet 2

UNITED STATES PATENT OFFICE.

WALTER KENNEDY, OF CLIFFSIDE, NEW JERSEY.

GAS HEATER.

Application filed November 14, 1925, Serial No. 68,931. Renewed January 16, 1928.

My invention relates to improvements in gas heaters, and more particularly has reference to what is generally known as the radiant type of heater, in which slabs, blocks, or other forms of clay are heated by the combustion of the gas, radiating the heat into the room or chamber where used.

Referring to the accompanying drawings, I have illustrated in Fig. 1, in perspective, parts being broken away, a suitable form of heater embodying an application of my invention. Fig. 2 is a cross-sectional view of the same illustrating modifications.

3, 3' indicate the front corner columns and legs of the heater, the back legs being preferably formed of angle iron as shown at 4. 5 indicates the top frame preferably U-shaped as shown and adapted to retain the back 6 which is preferably of sheet metal 20 and may be provided with holes such as 7. Beneath the front of the heater is preferably secured a channel 8, providing support for the forwardly extending lugs 9 of the burner 10, and above said channel 8 is secured the front portion of a plate 11, provided with a longitudinal lug 12, behind which is held upon said plate, the heavy radiant 13, the back of said radiant 13 being also supported upon the front edge of the back portion of said plate which also has a longitudinal lug or rib 15, behind which is mounted the fire-clay block or insulator 16 as shown.

Beneath the back of the plate 11 is secured the manifold 17, provided with a gas inlet 18, and outlet 19 in line with the Bunsen tube 20, of the burner 10. 21 is a funnel-shaped guide for the end of the tube 20, said guide being preferably secured by a lug 40 such as 22 beneath the back 14 of the plate, thus serving to centralize the burner 20 when placing the same in position.

23 indicates a front grille or bars extending between the side posts 3, 3', and between the same and the grilles 24 in front of and which may be formed with the radiants 13, may be secured artificial fuel such as 25, the same extending upwardly over the caps 26, which are provided with cut-away portions 50 27 to allow for the escape of heat rising between the artificial fuel 25.

The radiants 13 are preferably provided with corrugated faces 28 back of the grille 24, leaving an open space above the burners 10, and the sides of the radiants are pref-

erably cut down as indicated at 29 to allow for intercommunication of the gaseous mixture from one section to the other of the heater, each section preferably including a radiant and its grille, as well as an insulating block and burner. At the ends of the heater, additional insulating blocks such as 30 may be inserted, as shown.

With an arrangement such as shown, it will be readily understood that by raising 65 the fronts of the burners, they may be lifted off the channel support 8, and conveniently replaced and centralized by virtue of the funnel-like guide 21, and each section of the heater may be manipulated independently 70 if desired. The products of combustion from each burner pass upwardly between the grille 24 and corrugated face 28 of the radiant, and through the openings 27 in the tops 26. The artificial fuel is preferably 75 formed and colored to simulate natural coal and becomes incandescent when heated, thus presenting the appearance of a burning coal basket.

In the modification shown in Fig. 2, the 80 front grille 23 is omitted, and a front angle piece 31 is preferably added at the base as shown, the same being connected to the front 11 of the plate and also to the channel 8, by any suitable means such as screws 32. The 85 burners are also preferably provided with ribs 33 which radiate the heat from the burner, and the manifold 17 may be provided with a flange 17' secured through the back of the heater by screws 34.

The burners are preferably made of cast iron, and are preferably cut-away providing parallel paths or channels as indicated at 35. They are then cut at right angles thereto providing a series of parallel projections 36. This milling out of the cast iron provides narrow openings between parallel segments, through which the gas and air escape both upwardly and laterally through the cuts. Secondary air in the channels 100 thus formed, mixes with the outpouring air and gas, and also tends to cool the burner, and in doing so is in turn heated immediately before combustion, the heavy metal of the burner and radiating ribs thereof serving 105 while dissipating the heat of the burner to heat the air in the immediate neighborhood thereof.

The nozzle or tip 37 is also preferably provided with a knife edged orifice as in- 110

dicated at 38 which produces better mixture and is more efficient. The radiant 13 is preferably of substantial thickness or mass, and when heated by the flame it retains a substantially uniform heat through the mass thereby insuring more perfect combustion and maximum radiation irrespective of any form of grille in front thereof.

Of course it will be understood that various modifications may be made in the construction and arrangement of parts without departing from the spirit of my invention as claimed.

I claim:—

- 15 1. In a heater of the class described, several sections, each of which include an insulating member, a radiant in front of the same, a fire-clay top over the same, and passage for the products of combustion through said radiant, a burner beneath said passage, and openings through said top for the passage of said products of combustion, said radiant having a grille-like front, and

all of said sections within an outer framework closed at the back and ends.

25

2. In a heater of the class described, an outer frame open at the front and top, a burner supported in the bottom with the head thereof at the front, a radiant over said burner having a spaced apart grille-like face, fuel simulating material within said frame and retained in front of said radiant and over the top of the same.

3. In a heater of the class described, an outer frame open at the front and top, a burner supported in the bottom with the head thereof at the front, a radiant over said burner having a spaced apart grille-like face, fuel simulating material within said frame and retained in front of said radiant and over the top of the same, and bars in front of said fuel simulating material.

35 In testimony whereof I hereunto affix my signature.

WALTER KENNEDY.
